UNITED STATES PATENT OFFICE.

STEPHEN OCTAVE DELAUNE, OF RACELAND, LOUISIANA.

CHIMNEY-COWL.

1,261,719.

Specification of Letters Patent.

Patented Apr. 2, 1918.

Application filed July 10, 1917. Serial No. 179,696.

To all whom it may concern:

Be it known that I STEPHEN OCTAVE DELAUNE, a citizen of the United States, residing at Raceland, in the parish of Lafourche, 5 State of Louisiana, have invented a new and useful Chimney-Cowl; and I do hereby declare the following to be a full, clear, and exact description of the invention, such as will enable others skilled in the art to which 10 it appertains to make and use the same.

The present invention relates to certain new and useful improvements in chimney cowls, and has for its object to provide a device of this character which embodies novel 15 features of construction whereby it can be readily applied to a chimney, smoke pipe, or ventilating tube, and will operate in an effective manner to prevent the wind from blowing down the chimney or smoke pipe 20 and interfering with the draft through the same.

Further objects of the invention are to provide a device of this character which can be easily and quickly placed in position 25 or removed therefrom, which can be adjusted to fit the particular chimney or smoke pipe with accuracy, which will revolve freely under the action of the wind, and which is not liable to break or get out of repair.

With these and other objects in view, the invention consists in certain novel combinations and arrangements of the parts as will more fully appear as the description proceeds, the novel features thereof being point- 30 ed out in the appended claims.

For a full understanding of the invention, reference is to be had to the following description and accompanying drawings, in which:—

40 Figure 1 is a side elevation of a chimney cowl constructed in accordance with the invention.

Fig. 2 is a similar view looking at the device from a position at right angles to that 45 indicated by Fig. 1.

Fig. 3 is a vertical longitudinal sectional view through the cowl and the upper portion of the smoke stack.

Fig. 4 is a top plan view of the bracket 50 for supporting the hood of the cowl.

Corresponding and like parts are referred to in the following description and indicated in all the views of the drawings by the same reference characters.

55 Referring to the drawings, which illustrate one embodiment of the invention, the

numeral 1 designates the upper end of a chimney or smoke pipe of the conventional construction. The revolving hood A is mounted upon a vertically disposed pivot 60 shaft 2 which is supported in position by a series of arms 3 radiating from the base thereof. These supporting arms 3 are rigid with the pivot rod and have the ends thereof extended downwardly at 3^a, the extremities of 65 the arms being provided with clips 4 which fit over and engage the upper edge of the smoke pipe 1. Any suitable means, such as the clamping screws 5 may be provided for locking the clips 4 in position upon the up- 70 per edge of the smoke pipe. The downwardly extended ends 3^a of the supporting arms can be bent inwardly or outwardly to bring the clips 4 into proper position for engaging the smoke pipe, thereby enabling the 75 device to be adjusted to fit different sizes of smoke pipes, within certain limits.

The revolving hood A includes a circular top 6 and peripheral side walls 7 which extend downwardly from the edges of the top, 80 said hood being open at the bottom thereof and adapted to telescope over the upper end of the smoke pipe. An opening or cut-away portion 8 is formed in one side of the hood A, and a vane 9 which extends diametrically 85 across the top of the hood and projects from the sides thereof is arranged in such a relation to the cut-away portion 8 as to hold the latter on the leeward side of the smoke pipe when the wind blows. 90

A tubular bearing 10 projects upwardly from the center of the top 6 of the hood A and receives the before mentioned vertical pivot rod 2 of the supporting frame. The vane 9 is suitably cut-away to receive the 95 bearing sleeve 10, and a slide 11 which is mounted upon the vane is adapted to be moved into a slot 12 in one side of the bearing sleeve 10 and engage an annular groove 13 in the pivot rod 2 to lock the sleeve against 100 vertical movement on the pivot rod and hold the hood in position, at the same time permitting it to rotate freely about a vertical axis.

The downward bent ends 3^a of the supporting arms 3 preferably have horizontally disposed anti-friction rollers 14 journaled thereon, said rollers being positioned between the clips 4 and collars 15. These rollers engage the depending sides 7 of the 110 hood and prevent rattling or binding at the base of the hood. The portion of the side 7

2
of the hood under the opening or cut-away portion 8 thereof is split and overlapped, one of the overlapping ends being formed with a series of slots 16, while the other overlapping end is formed with a tongue 17 adapted to be inserted through any selected one of the slots and then returned to lock the parts in an adjusted position. This construction admits of the lower end of the hood being 10 expanded or contracted within certain limits to bring it into a proper engagement with the anti-friction rollers 14, thereby enabling the device to be fitted with accuracy upon any particular chimney or smoke pipe.

15 Having thus described the invention, what I claim as new and desire to secure by Letters Patent, is:—

1. A chimney cowl including a pivot rod, a series of supporting arms radiating from 20 the base of the pivot rod and provided with chimney engaging means, anti-friction rollers upon the supporting arms, a hood mounted over the top of the chimney and having a cut-away portion in one side thereof, the 25 sides of the hood telescoping over the upper end of the chimney and being engaged by the before mentioned anti-friction rollers, a bearing sleeve applied to the top of the hood and receiving the pivot rod, and a vane 30 fitted upon the hood in position to hold the cut-away portion thereof on the leeward side of the chimney.

2. A chimney cowl including a pivot rod, a series of supporting arms radiating from 35 the base of the pivot rod and terminating in clips adapted to engage the chimney, anti-friction rollers journaled upon the arms, a hood arranged over the chimney and having a cut-away portion in one side thereof, the lower end of the hood telescoping over 40 the upper end of the chimney and being expandible so as to be brought into a proper engagement with the before mentioned rollers, a tubular bearing applied to the top of the hood and receiving the pivot rod, and a vane applied to the hood in position for 45 holding the cut away portion thereon on the leeward side of the chimney.

3. A chimney cowl including a pivot rod, 50 a series of supporting arms radiating from the base of the pivot rod and having the ends thereof extended downwardly and provided with clips adapted to engage the chimney, horizontally disposed anti-friction rollers journaled upon the downwardly 55 extended ends of the supporting arms above the clips, a hood mounted over the chimney and having a cut-away portion in one side

thereof, the sides of the hood being slit and formed with overlapping edge portions 60 which adjustably engage each other so that the sides of the hood can be brought into a proper engagement with the anti-friction rollers, a tubular bearing applied to the top of the hood and receiving the pivot rod, and 65 a vane fitted upon the hood in position to hold the cut-away portion thereof on the leeward side of the chimney.

4. A chimney cowl including a pivot rod 70 having an annular groove therein, a series 75 of supporting arms radiating from the base of the pivot rod and provided with means for engaging the chimney, a hood arranged over the top of the chimney and having a cut-away portion in one side thereof, a bearing sleeve extending upwardly from the top of the hood and receiving the pivot rod, said bearing sleeve having a slot in one side thereof, a vane extending across the top of the hood and arranged to hold the cut-away portion thereof on the leeward side of the chimney, and a locking slide mounted upon the vane and adapted to be moved into the slotted portion of the bearing sleeve 80 for engagement with the groove of the pivot 85 rod to hold the hood in position.

5. A chimney cowl including a pivot rod provided with an annular groove, a series 90 of supporting arms radiating from the base of the pivot rod and terminating in clips adapted to engage the chimney, anti-friction rollers journaled upon the supporting rods, a hood mounted over the top of the chimney, said hood having a cut-away portion 95 in one side thereof and being engaged at the lower end thereof by the before mentioned rollers, a bearing sleeve projecting upwardly from the hood and receiving the pivot rod, said bearing sleeve having a slot in one side thereof, a vane extending across 100 the top of the hood and arranged to hold the cut-away portion thereof on the leeward side of the chimney, and a locking slide mounted upon the vane and adapted to be moved into the slotted portion of the bearing sleeve 105 to engage the annular groove of the pivot rod and lock the hood in position.

In testimony whereof I have signed my name to this specification in the presence of 110 two subscribing witnesses.

STEPHEN OCTAVE DELAUNE.
